UNITED STATES PATENT OFFICE

AMOS E. NORTHUP, OF PLEASANT RIDGE, MICHIGAN, ASSIGNOR TO THE MURRAY CORPORATION OF AMERICA, OF DETROIT, MICHIGAN, A CORPORATION OF DELAWARE

DESIGN FOR AN AUTOMOBILE

Application filed January 18, 1933. Serial No. 46,874. Term of patent 7 years.

To all whom it may concern:

Be it known that I, AMOS E. NORTHUP, a citizen of the United States, a resident at Pleasant Ridge, in the county of Oakland, State of Michigan, have invented a new, original, and ornamental Design for Automobiles, of which the following is a specification, reference being had to the accompanying drawings, forming a part thereof, wherein:

Figure 1 is a front view of an automobile embodying my design;

Fig. 2 is a plan view of the automobile illustrated in Fig. 1.

Fig. 3 is a reduced side view of the automobile illustrated in Fig. 1; and

Fig. 4 is a rear view of the automobile illustrated in Fig. 1.

I claim:

The ornamental design for an automobile as shown.

AMOS E. NORTHUP.
